JOSEPH SLEPIAN, OF SWISSVALE, AND SOLOMON M. PINELES, OF PITTSBURGH, PENNSYLVANIA, ASSIGNORS TO WESTINGHOUSE ELECTRIC AND MANUFACTURING COMPANY, A CORPORATION OF PENNSYLVANIA.

DISK-PILE LIGHTNING ARRESTER.

Application filed November 23, 1922. Serial No. 602,718.

This invention relates to lightning arresters, more particularly to lightning arresters, of the disk-pile type.

The disk-pile lightning arrester generally consists of a series or stack of disks or plates of high-resistance material, the thickness of the disks being small relative to the surface area thereof. Adjacent disks are spaced slightly apart to provide gaps across which a lightning or other abnormal discharge may pass to relieve the line, to which the lightning arrester is connected, of the disturbance. Said spacing of the disks may be obtained in a variety of ways, such as providing the adjacent surfaces of the disks with irregularities or ribs which may be of higher resistance than the body portion of the disks, said irregularities or ribs serving to hold the major portions of the disks in proper relation. The disks may be spaced in any other suitable manner, as by thin mica spacers interposed therebetween.

A pile of two or more disks of the above-designated character is connected to the circuit to be protected by metal end plates which make contact with the end disks of the lightning arrester unit. Upon the passage of a discharge through the assembly, difficulty has arisen by reason of the chipping or shattering of the end disks along the surface of contact with the metal plates, evidently resulting, in some way, from the heavy currents passing therethrough being concentrated at a relatively few points of contact at the high spots of the contacting disks and plates.

This invention is designed to overcome the difficulties just mentioned, it being among the objects thereof to provide a means for making electrical contact with the end disks of a lightning arrester which shall effectively prevent chipping or shattering of the same.

In practising our invention, we provide a series of two or more disks, as above set forth, and so form the surfaces of the end disks that they make excellent contact with the metal end plates in engagement therewith, this being accomplished by coating the surfaces of the end disks with highly conducting material by a method which insures close contact of said coating with the bodies of the disks. This is accomplished by either electroplating a metal, such as copper, there-

upon, or by spraying a suitable metal by a well known process, such as the Schoop metal-spraying process.

In the accompanying drawing constituting a part hereof and in which like reference characters designate like parts, the single figure is a vertical cross-sectional view of a disk-pile lightning arrester embodying our invention.

The disks or plates 1 of high-resistance material are spaced slightly apart by thin mica washers 2. Upon each of the end members of the series of disks, constituting the disk-pile unit, we form a coating 3 of metal by a suitable process, such as electroplating or spraying. The coating is firmly united with the surface of the end plates and constitutes an integral portion thereof. Metal end plates 4 are placed in contact with the coatings 3, and suitable conductor leads 5, electrically connected with end plates 4, provide means for connecting the unit into the circuit to be protected.

We are aware that it has been proposed to provide a rod of resistance material with coated ends in order that it may make good contact with the terminals of the circuit in which said rod is inserted. This was done for the purpose of preventing sparking from the terminal to the rod which gave the resistance of the poor contact instead of the resistance of the rod itself. Furthermore, flashover along the sides of the resistor rod was liable to occur owing to the poor contact. In our device, there is no danger of

sparking and flashover but the difficulty consists in the chipping and shattering of the end disks by reason of heavy currents passing between the metal end plate and the disk in contact therewith. This chipping and shattering, unless a coating such as we have described is used, cannot be avoided because of the concentration of the heavy currents at relatively few points of contact, even though the contact between said disk and plate is made as perfect as possible. Such difficulty does not arise in the prior structure, since said resistance rod does not carry high currents.

Although we have described our invention, setting forth a specific embodiment thereof, it is apparent that various modifications may be made therein within the scope

thereof. For instance, although we have mentioned the metal copper as being suitable for the purpose, other metals having good conductivity may be substituted therefor, or even non-metallic materials, such as graphite, may be used. Our invention is not confined to the specific form of disk-pile lightning arrester here described but other forms thereof may be used in conjunction with the subject matter of this invention.

We claim as our invention:

1. A disk-pile lightning arrester comprising a stack of disks of high-resistance material, the thickness of the disks being small relative to the surface area thereof, and metallic end plates in contact with the ends of the stack, the arrester being characterized by a thin metallic coating united with only the outer surface of each of the end disks of

the stack, whereby breakage of the disks is materially reduced.

2. A protective device of the disk-pile type comprising at least two very closely spaced electrode plates of high-resistance material, a metallic terminal member for at least one of said plates, means for holding said terminal member against the back surface of said plate, and a coating of a relatively good conducting material on said back surface, the opposed surfaces of the gaps between two adjacent electrode plates being of high-resistance material.

In testimony whereof, we have hereunto subscribed our names this 13th day of November, 1922.

JOSEPH SLEPIAN.
SOLOMON M. PINELES.
